UNITED STATES PATENT OFFICE.

JOHN FRANCIS REILLY, OF CENTRAL AGUIRRE, PORTO RICO.

OIL-BURNER.

1,292,371.

Specification of Letters Patent. Patented Jan. 21, 1919.

Application filed September 20, 1918. Serial No. 254,946.

To all whom it may concern:

Be it known that I, JOHN F. REILLY, a subject of the King of Great Britain, and a resident of Central Aguirre, in the county 5 of Guayama, Porto Rico, have invented a new and Improved Oil-Burner, of which the following is a full, clear, and exact description.

This invention relates to oil burners and 10 particularly to burners which may use crude oil as well as refined oil, and has for an object the provision of an improved construction wherein the oil is sprayed with steam in order to secure high efficiency.

15 Another object in view is to provide a burner having a steam and oil inlet with a mixing chamber and spraying chamber adjacent its discharge mouth so that the oil will be heated, sprayed and mixed with steam 20 substantially simultaneously.

A still further object of the invention is to provide a burner which is made in a minimum number of parts and which acts to produce a proper spray without utilizing any 25 moving parts.

In the accompanying drawing:

Figure 1 is a longitudinal vertical section through a burner disclosing an embodiment of the invention.

30 Fig. 2 is an end view of the burner shown in Fig. 1.

Fig. 3 is a top plan view of the burner shown in Fig. 1.

Fig. 4 is a rear end view of the structure 35 shown in Fig. 1.

Fig. 5 is a perspective view of the burner with a front section removed.

Fig. 6 is a perspective view of the front section of the burner shown in Fig. 5.

40 Referring to the accompanying drawing by numerals, 1 and 2 indicate the feed pipes, pipe 1 supplying steam under pressure, while pipe 2 supplies the fuel oil, which may be crude oil or refined oil as desired. These 45 pipes feed into what may be termed chambers 3 and 4 of the casing 5, which casing has substantially semi-circular openings 6 and 7 opening into the notch 8, which notch is filled by a removable front section 9 when

50 the burner is in use as shown in Fig. 1. This section fits snugly and is held in place by suitable screws 10 and 11. Section 9 covers the opening 7 except for the part which registers with the passageway 12, said passageway leading down to a mixing chamber 13. 55 The opening 6 is partially closed by the sec-

tion 9 with the exception of a small comparatively flat passageway 14 which is restricted at 15 so as to provide velocity for the steam as it enters the mixing chamber 13. The oil 60 is fed through the passageway 12 at comparatively slow speed while the steam moves at high speed so that the velocity of the mixture will be considerable and the steam and fuel will quickly and intimately mix into a 65 fine spray, which spray is ignited usually some distance from the burner. By reason of the mixing chamber 13 and the way the passageways 12 and 14 are provided the discharge mouth or opening 15 directs a combustible mixture to a comparatively great distance or short distance according to the force of the steam. In order to secure the maximum result the mouth 15 is provided with diverging walls 16 and 17 whereby the 70 discharge is substantially confined between the dotted lines shown in Fig. 3, said discharge being in a flat horizontal sheet. The fuel oil and the steam are supplied in any desired volume and any desired proportion, 75 the proportion being, of course, adjusted to produce the most efficient action when mixed with the air supplied by any desired air supplying structure.

The burner may be used in steam boilers 85 or in heating devices of any kind where there is a space for the proper use of the sprayed fuel provided by the burner. In connection with the restricted portion 15 it will be observed that the same is restricted vertically, 90 but as shown in Figs. 2 and 6, said restricted portion is gradually widened from the inner to the outer end of the passageway 14 so as to provide a thin spray or sheet of steam at comparatively high speed in order to break 95 up the fuel oil entering the chamber 13 through passageway 12.

What I claim is:

1. A burner comprising a casing having a pair of spaced chambers, and a notch in the 100 front end merging into the lower part of the upper chamber and the upper part of the lower chamber, the bottom of the notch being flat, a removable section fitting into said notch, said removable section having a discharge opening merging into the mixing chamber, said discharge opening and mixing chamber having diverging walls, the upper face of the discharge opening being parallel with the lower face of said notch, 105 whereby the discharge through the discharge opening will be in a thin horizontal sheet, a 110

passageway extending from one of said chambers into said mixing chamber in line with the lower part thereof, and a second passageway extending at an appreciable 5 angle to the mixing chamber and merging into the mixing chamber and into one of said first mentioned chambers.

2. A burner comprising a casing having an upper and lower chamber, said upper 10 chamber being adapted to receive a liquid fuel and the lower chamber adapted to receive steam under pressure, a flat horizontal

passageway extending from said lower chamber, said passageway being restricted vertically toward the outer end thereof, a 15 diagonal fuel passageway extending from said fuel chamber to a point intersecting the first mentioned passageway, and a mixing chamber at the juncture of said passageways merging into a discharge opening, said discharge opening being in the form of a horizontal slot whereby there will be produced a sheet of mixed liquid fuel and steam.

JOHN FRANCIS REILLY.
